(57) **CLAIM**

The ornamental design for a spinning reel rotor for fishing, as shown and described herein.

DESCRIPTION

FIG. 1 is a front, plane, right side perspective view of a spinning reel rotor for fishing showing the new design; FIG. 2 is a back, bottom, left side perspective view of a spinning reel rotor for fishing of FIG. 1 showing the new design; FIG. 3 is a front view of the spinning reel rotor for fishing of FIG. 1 showing the new design;

FIG. 4 is a rear view of the spinning reel rotor for fishing of FIG. 1 showing the new design;

FIG. 5 is a plan view of the spinning reel rotor for fishing of FIG. 1 showing the new design;

FIG. 6 is a bottom view of the spinning reel rotor for fishing of FIG. 1 showing the new design;

FIG. 7 is a right side view of the spinning reel rotor for fishing of FIG. 1 showing the new design;

FIG. 8 is a left side view of the spinning reel rotor for fishing of FIG. 1 showing the new design; and,

FIG. 9 is a perspective view showing the spinning reel rotor for fishing of FIG. 1 in an environment of use.

(Continued)

The broken lines in the drawings depict environment and form no part of the claimed design.
